UNITED STATES PATENT OFFICE.

MURDOCK MACDONALD, OF CLEVELAND, OHIO.

AUTOGRAPHIC REGISTER.

Application filed May 12, 1920. Serial No. 380,711.

To all whom it may concern:

Be it known that I, MURDOCK MACDONALD, a citizen of the United States, and a resident of Cleveland, county of Cuyahoga, and State of Ohio, have invented a new and useful Improvement in Autographic Registers, of which the following is a specification, the principle of the invention being herein explained and the best mode in which I have 10 contemplated applying that principle, so as to distinguish it from other inventions.

The present invention relates to an autographic register, the principal object of the invention being the provision in such a device of a simplified means for discharging the superimposed sheets from the mechanism. Other objects of the invention will appear from the following description. To the accomplishment of the foregoing and related ends, said invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawings:—

Fig. 1 is a side elevation partially in section of my improved register; Figs. 2 and 3 are enlarged side elevations of the discharging mechanism in two positions; Fig. 4 is a front elevation of the discharging rolls; Fig. 5 is a plan view of the device; Fig. 6 is a section on the line 6—6, Fig. 5; and Fig. 7 is an end elevation of the magazine roll and driving mechanism.

In Fig. 1 I have shown my improved register, which consists of a box-like framework 1 of substantially rectangular form provided with a removable and slightly inclined cover plate 2. This cover plate is provided with a tearing-off edge 3, a glass plate 4 adjacent to the forward end of the plate, and with an opening 5 for permitting writing upon the sheets of paper, which are brought forward directly beneath the cover and beneath this opening. The cover is also provided with semi-cylindrical extensions 6 adapted to enclose one of the discharging rolls, and with a longitudinally extending slot 7 in which the reciprocating discharge mechanism will be operated, as will be described later.

Housed in the framework 1 are three

paper-receiving rollers 8, 9 and 10. The several sheets of paper 8', 9' and 10' over these several rollers are carried rearwardly and passed over guide rolls 11, 12 and 13, 60 respectively, and are then passed over a table 14, which extends from the rear of the device to a point adjacent to the discharge rollers 15 and 16. These sheets of paper, which may be either two, three or more in 65 number, must be maintained in exact registration during their passage through the machine, and if they are not the printed memorandum which usually appear upon such strips will not register, and any notes 70 made on the uppermost sheets through the writing recess 5 will not appear in the proper positions on the sheets below.

The discharge roller 15 is a metal roller provided with a knurled surface 18 and carried in slots 19 formed in brackets on either side of the framework 1, thus allowing this roller to move vertically and to rest upon the paper by its own weight. The other discharge roller 16 may be either of rubber 80 or of some other frictional material, and is preferably provided with a series of longitudinally extending projections or ribs 19, which serve to give a secure grip upon the sheets of paper passing between it and the 85 roll 15. This roller 16 carries a gear 20 which is engaged by means of a second gear 21 adapted to be operated by a rack 22 formed on a reciprocating plate or bar 23. Mounted beneath the discharge rollers in 90 the frame is a magazine roller 24 adapted to receive the lowermost sheet of the several passing through the machine, and storing the same for purposes of record. This roller is provided with a gear 25 and is driven 95 through that gear and through other gears 26 and 27, the gear 27 being operated by the same rack mechanism 22 which operates the discharge rollers.

The roller 24 is driven by the gear 25 100 through a spring 50 interposed between this gear and two fibre discs 51 and 52 which are pressed against a metal disc 53 attached to the roll 24. These parts are assembled with the spring 50 under compression and 105 the friction thus produced provides a driving engagement between the fibre and metal discs. The former are attached to the shaft 54 while the roller 24 and metal disc 53 are loose on this shaft. In this way a frictional driving means is provided which may be set to slip after a predetermined resist-

ance has been established as will be the case as soon as the diameter of the magazine roll has been increased over its initial size.

The gear 27 is operated through one way 5 ball clutches (not shown) similar to those shown in Figs. 2 and 3.

The gear 20 is attached to the roller 16 by means of ball clutches 28 which operate in slots 29 formed in the gears 20, and also 10 in similar recesses formed in the ends of the rollers 16. These ball clutches are of the usual one-way type which is commonly used to provide a drive in one direction only and allows the reciprocating bar 23 to actuate 15 the discharge roller 20 only in the direction of the arrow shown in Fig. 1. Upon the return of the reciprocating bar 23 the gear 20 is disengaged from the roller 16 so that the paper will remain stationary upon the 20 return movement of the reciprocating carriage.

The reciprocating plate 23 is provided at its rear end with an upwardly extending arm 30, which is attached to a slidably 25 mounted bridge 31. This bridge consists of a transverse lower plate and a transverse upper plate 32, which is provided with upwardly extending lugs 33, between which is pivotally mounted an operating handle 34. The lower end of this handle 34 carries a roller 35, which is adapted to be 30 pressed against the several sheets of paper 10', 9' and 8', which are passed between the upper and lower members of the bridge. 35 In order to actuate the paper forward and discharge the two uppermost sheets from the machine, the operator presses forward on the handle 34, that is, he presses it towards the forward end of the machine. This action 40 first engages the roller 35 against the paper and clamps the paper to the bridge and reciprocating carriage. It next actuates the entire bridge and carriage forward, pushing the rack 22 forward between the 45 gears 21 and 27, and of course actuating these gears as the rack goes forward. This action rotates the discharge roller 16 and passes the paper between this roller and the undriven roller 15 until the paper has been 50 forced out of the front of the frame where it can be torn off against the tearing-off edge 3. The reciprocating carriage is then returned to its original position by pulling back on the handle 34, which first releases 55 its grip upon the paper and then draws the carriage back, but without actuating the discharge mechanism as the latter are disengaged by the ball clutches 28.

Other modes of applying the principle of 60 my invention may be employed instead of the one explained, change being made as regards the mechanism herein disclosed, provided the means stated by any of the following claims or the equivalent of such 65 stated means be employed.

I therefore particularly point out and distinctly claim as my invention:—

1. In an autographic register, the combination of an enclosing casing, a plurality of paper-carrying rollers mounted in said casing, a pair of paper-discharging rolls mounted in said casing, a reciprocably mounted longitudinal carriage, means mounted at one end of said carriage adapted to actuate one of said discharge rolls, and means mounted at the other end of said carriage adapted to simultaneously draw paper from said carrying rollers to said discharge rolls. 70

2. In an autographic register, the combination of an enclosing casing, a plurality of paper-carrying rollers mounted in said casing, a pair of paper-discharge rolls mounted in said casing, a reciprocably mounted longitudinal carriage movable toward and away from said discharge rolls, the paper from said carrying rolls passing over said carriage and between said discharge rolls, means mounted at one end of the carriage adapted to actuate one of said discharge 90 rolls, and means mounted at the other end of said carriage adapted to grip the paper and move the same with said carriage in its forward movement. 95

3. In an autographic register, the combination of an enclosing casing, a plurality of paper-carrying rollers mounted in said casing, a pair of paper-discharging rolls mounted in said casing, a reciprocably mounted carriage movable toward and away from said discharging rolls, and provided with means adapted to actuate one of said discharging rolls the paper from said carrying rolls passing over said carriage and between said discharge rolls, manually operable clamping means on said carriage, said means being adapted to clamp such paper against movement relative to said carriage during one-direction movement of the same. 100

4. In an autographic register, the combination of an enclosing casing, a plurality of paper-carrying rollers mounted in said casing, a pair of paper-discharging rolls mounted in said casing, a reciprocably mounted carriage movable toward and away from said discharging rolls, the paper from said carrying rolls passing over said carriage and between said discharge rolls, means on said carriage adapted to grip such paper and move the same with said carriage, and other means adapted to actuate said discharge rolls to discharge such paper upon one-direction movement of said carriage. 115

5. A reciprocable carriage for mechanism of the character described, comprising a slidably mounted frame, spaced transverse elements on said frame adapted to receive sheets of paper therebetween, and manually operated means for actuating said 120 carriage. 125

130

frame, said means being adapted to clamp said elements firmly against such sheets for one direction movement of said frame and to release the clamping of said elements during the reverse movement of the frame.

6. A reciprocable carriage for mechanism of the character described, comprising a slidably mounted frame, spaced transverse elements on said frame adapted to receive sheets of paper therebetween, and a clamping lever pivotally mounted on one of said transverse elements, said lever being adapted to clamp such sheets firmly against the

other of said transverse elements for movement with said carriage. 15

7. In apparatus of the character described, the combination of a reciprocably mounted carriage having a longitudinally extending double rack element thereon, gears fixedly mounted on either side of said rack element operable thereby upon movement of said carriage, and said gears serving as one guide and support for said carriage. 20

Signed by me this 10th day of May, 1920.
MURDOCK MACDONALD.
